UNITED STATES PATENT OFFICE.

RENÉ LALIQUE, OF PARIS, FRANCE.

DESIGN FOR A GLASS BOX OR SIMILAR ARTICLE.

Application filed April 24, 1923. Serial No. 5,923. Term of patent 3½ years.

To all whom it may concern:

Be it known that I, RENÉ LALIQUE, a citizen of the Republic of France, and a resident of Paris, France, have invented a new, original, and ornamental Design for a Glass Box or Similar Article, of which the following is a specification, reference being had to the accompanying drawing, forming a part thereof, and in which—

Fig. 1 is a side view, and

Fig. 2 a top view of a glass box showing my new design.

The design consists in a cluster of powder-puffs grouped within a circle to display the puffs and their stems beneath an arched transparent surface.

I claim:

The ornamental design for a glass box or similar article, as shown.

RENÉ LALIQUE.
